BILLFOLD

Sidney Hyman, New York, N. Y.

Substituted for abandoned application Serial No.
513,023, December 6, 1943. This application
July 3, 1948, Serial No. 37,114

2 Claims. (Cl. 150—38)

1

This invention relates to new and useful improvements in a bill fold.

More specifically, the invention proposes the construction of a bill fold designed to be made of leather or other similar material and which is of a construction to materially reduce waste of the leather material when cutting the pieces from which the bill fold is formed.

Still further it is proposed to characterize the bill fold by an outer flexible sheet having a horizontal rectangular section of a slightly larger size than the bills to be placed in the bill fold, and three slightly separated vertical rectangular sections continuing from the bottom edge of the horizontal section with the end vertical sections adapted to be bent upwards and have their top, bottom and outer side edges secured to an inner flexible sheet in a manner to form pockets having inner side openings.

It is further proposed to attach the side and bottom edges of the inner flexible sheet to the side and bottom edges of the horizontal section of the outer flexible sheet in a manner to form a bill pocket having an open top.

Still another object of the invention proposes providing the central vertical sections with a piece of flexible material attached thereto at its side and bottom edges, forming a pocket having an open top.

Still another object of the invention proposes attaching a top cover flap to the central portion of the top edge of the horizontal rectangular section to be cooperative with the central vertical section after the end portions of the horizontal section have been bent inwards to maintain the bill fold in a closed folded position.

Still another object of the invention proposes providing a change pocket upon the central portion of the horizontal rectangular section which is provided with an expanding front wall in a manner to permit the carrying capacity of this pocket to be increased by expanding the said wall.

Still another object of the invention proposes providing a means for movably mounting the pocket located on the central portion of the horizontal section to be shiftable into either of the side pockets formed upon the horizontal section.

For further comprehension of the invention, and of the objects and advantages thereof, reference will be had to the following description and accompanying drawings, and to the appended claims in which the various novel fea-

tures of the invention are more particularly set forth.

In the accompanying drawings forming a material part of this disclosure:

5 Fig. 1 is a perspective view of a bill fold constructed in accordance with this invention, and in its completely closed position.

Fig. 2 is a rear perspective view of Fig. 1.

10 Fig. 3 is a perspective view illustrating a partially opened position of the bill fold.

Fig. 4 is a perspective view illustrating the completely opened position of the bill fold.

15 Fig. 5 is an enlarged longitudinal horizontal sectional view taken on the line 5—5 of Fig. 4.

Fig. 6 is a vertical sectional view taken on the line 6—6 of Fig. 4.

Fig. 7 is a vertical sectional view taken on the line 7—7 of Fig. 4.

20 Fig. 8 is an inside elevational view of a bill fold constructed in accordance with a modification of this invention and in its completely opened position.

Fig. 9 is an enlarged partial horizontal sectional view taken on the line 9—9 of Fig. 8.

25 Fig. 10 is a perspective view of the bill fold, according to this invention, comprises an outer flexible sheet 10 of leather or other similar material which has a horizontal rectangular section 11 of a size slightly larger than the bills to be placed in the bill fold and three slightly separated vertical rectangular sections 12, 13 and 14 continuing from the bottom edge thereof. The endmost vertical sections 12 and 14 are bent upwards into a superimposed position upon the ends of the horizontal section

30 11. An inner flexible sheet 15, also of leather or other similar material, is disposed behind the end vertical sections 12 and 14 and is arranged congruent with the horizontal section 11. Stitches are provided for attaching the sides and

40 the bottom of the inner flexible sheet 15 to the sides and the bottom of the horizontal section 11 for forming a horizontal pocket 16 having an open top into which bills are adapted to be engaged. Stitches 17 attach the top, bottom and outer side edges of the endmost sections 12 and 14 to the adjacent edges of the inner flexible sheet 15. This forms pockets 18 having inner open sides.

45 A flexible sheet 19 is disposed upon the central section 13. This flexible sheet 19 has its side and bottom edges attached to the adjacent edges of the central section 13 by means of stitches 20 forming a pocket 21 having an open top.

50 A top cover flap 21 is attached to the central portion of the top edge of the horizontal rec-

tangular section 11 and is arranged to cooperate with the central section 13 to maintain the bill fold in a closed position which will be more fully described as this specification proceeds.

A pocket 22 is mounted in position upon the central portion of the inner flexible sheet 15. This pocket 22 is formed of material consisting of a front wall 23 which continues at its bottom edge into a vertical back wall 24, which in turn continues into a closure flap 25. The front wall 23 is provided with several expandable gussets 26 which are adapted to be extended for increasing the carrying capacity of the pocket 22. Snap fasteners 27 are arranged between the flap portion 25 and the front wall portion 23 for maintaining the open top of the pocket 22 closed by the flap portion 25.

As shown in Fig. 3, the end portions of the central horizontal section 11 are adapted to be bent into position on the central portion thereof and the bottom central section 13 is adapted to be bent into a superimposed position upon these superimposed end portions, as shown in Fig. 1. The free edge of the top cover flap 21 is adapted to be bent downwards over the free top edge of the bottom vertical section 13. A snap fastener element 27 is mounted on the flap 21 and is adapted to be engaged with a complementary snap fastener element 28 on the central vertical section 13 for maintaining the bill fold in its folded closed position.

The junction portion of the top cover flap 21 is provided with a pair of spaced eyelets 29. These eyelets 29 are adapted to have a long or short key chain or other articles attached thereto.

The upwardly bent end sections 12 and 14 and the flexible sheet 19 secured in position upon the central section 13 are formed with central openings 30 forming frame-like panels. These central openings 30 are adapted to be closed by means of transparent sheets 31 for permitting pictures to be carried within these pockets and to be easily viewed in the open condition of the bill fold.

In the form of the invention shown in Figs. 8 and 9 the pocket 22' disposed upon the central portion of the inner flexible sheet 15 is slidably mounted upon straps 35. The straps 35 are passed through aligned slots 36 formed in the sides of the pocket 22' permitting the pocket to be moved relative to the straps. The free ends of the straps 35 are projected into the pockets formed by the upwardly bent end sections 12 and 14 and are secured in position within these pockets. The provision of slidably mounting the pocket 22' upon the straps 35 permits the pocket to be shifted relative to the inner flexible sheet 15 to locate the pocket 22' within either of the pockets formed by the upwardly bent end sections 12 and 14.

In other respects this form of the invention is similar to that previously shown and like reference numerals identify like parts in each of the several views.

This application is a substitute for abandoned application Serial No. 513,023, filed December 6, 1943.

While I have illustrated and described the preferred embodiments of my invention, it is to be understood that I do not limit myself to the precise constructions herein disclosed and the right is reserved to all changes and modifications coming within the scope of the invention as defined in the appended claims.

Having thus described my invention, what I claim as new, and desire to secure by United States Letters Patent is:

1. A bill fold having three adjacent panels adapted to be folded into a superimposed position with pockets formed on the inner face of each of the outer panels which are open along their inner edges, a pocket positioned on the center panel, and means for horizontally slidably supporting said pocket to be movable into either of the pockets on the outer panels when desired, said means for slidably supporting said pocket comprising vertically spaced horizontal straps extended across said center panel and having their ends projected into the pockets on said outer panels, means securing said straps in position in said pockets on said panels, said pocket being formed at its sides with vertically spaced horizontally aligned pairs of slots through which the intermediate areas of said straps pass.

2. A bill fold having a plurality of adjacent panels adapted to be folded into a superimposed position with pockets formed on the inner face of the outer panels which are open along their inner edges, a pocket positioned on a central panel, and means for horizontally slidably supporting said pocket to be movable into pockets on the outer panels when desired, said means for slidably supporting said pocket comprising vertically spaced horizontal straps extended across said center panel and having their ends projected into the pockets on said outer panels, means securing said straps in position in said pockets on said panels, said pocket being formed at its sides with vertically spaced horizontally aligned pairs of slots through which the intermediate areas of said straps pass.

SIDNEY HYMAN.
